CASING MACHINE

Leonard McGihon, San Leandro, Calif., assignor to
Anthony R. Silva

Filed July 6, 1954, Ser. No. 441,350

4 Claims. (Cl. 53—243)

The present invention relates to casing machines of the case inverting type and is concerned more particularly with an improved machine of this character which facilitates a smooth case handling operation during the inversion thereof, and particularly during the discharge of an inverted case.

In casing machines of the character disclosed in the copending application of Anthony R. Silva, Serial No. 290,864, filed May 31, 1952, now Patent No. 2,786,316, an array of bottles is formed of the required number to fill a case, these bottles being fed in a series of parallel files, and the case is placed thereover in inverted condition. Subsequently the bottles with the case thereon are picked up from their split supports by a parallel series of lift arms and the case is inverted and deposited on a discharge conveyor, the conveyor in this type of machine being normally placed at a lower level than the position of the bottle array.

In accordance with the instant invention, a conveyor of a split type is provided to receive the case as it is leaving the lift arms after being inverted, and provides for a general rolling depositing of the case onto the conveyor for discharge. The conveyor is preferably of a split type so as to permit passage of the lift arms after discharge of a case for subsequent positioning in readiness to lift another array of bottles and case thereon from the casing station.

The above and other objects of the invention are attained as described in connection with a preferred embodiment thereof, as illustrated in the accompanying drawings, in which:

Figure 1 is a fragmentary side elevational view of a casing machine embodying the instant invention.

Figure 2 is a view similar to Figure 1, but illustrating another operating position of the casing mechanism.

Figure 3 is a plan view of the machine in the position illustrated in full lines in Figure 2.

Referring to the drawings, there is shown a casing mechanism including a feed conveyor 10 for a series of parallel files of bottles 11, this conveyor 10 feeding the bottles to a suitable casing mechanism 12 where the bottles are formed into a suitable case array for example 24 bottles to the case, for placing of the case 13 thereover in inverted position. The casing station 12 is constructed as disclosed in the copending application of Leonard McGihon, Serial No. 328,889, filed December 31, 1952, and entitled Bottle Spreader, now Patent No. 2,755,611, and reference is made to said application for details of construction not disclosed herein. In general the casing station includes a series of pairs of split rails 16 (Figure 3) providing an opening 17 therebetween through which an associated lift arm 18 may pass to engage a row of bottle and lift them with the case thereon. The lift arms 18 as seen in Figure 1 are formed in pairs and spaced 180° apart, being secured on a drive and support shaft 19 in a conventional manner, and having attached thereto a case supporting member 21 of suitable structure to engage the end of the case during the case

2

inverting operation. The shaft 19 is driven in a manner disclosed in said Silva application by a chain 22 from a transmission 23 including a cyclically operable clutch providing one half rotation of the shaft 19 for each cycle thereof. The transmission 23 also provides a suitable drive through the chain 24 for the feed conveyor 10.

As shown in the drawings (see Figure 3), there are four parallel lift arms 18 in each set and these arms are connected and driven together as a unit to first lift up through the split support structure 16 at the casing station. In their home position as shown in Figure 1, the arms 18 are inclined slightly from the vertical, the upper arm 18 being driven slightly beyond the vertical so as to impart a tilting movement to the case 13 engaged therewith. The case 13 in Figure 3 is at its beginning discharge position where it has already rolled away from the corresponding arms 18 and started its rolling descending movement.

Means are provided for receiving the case from the lift arms, and for continuing the tilting movement as smooth rolling movement in discharge thereof, and this means comprises a split support or conveyor in the form of two parallel series of rollers 31 carried by spaced arms 32, the arms 32 being mounted on shafts 33 and being held in spaced apart position by suitable spacers 34. The shafts 33 are carried by a pair of parallel adjustable brackets or plates 36 on a pair of projecting channel pieces 37 from the main frame 38. These channel pieces 37 are each provided with a series of longitudinally spaced holes 37a therealong, and these holes cooperate with a rectangular array of longitudinally and vertically spaced holes 39 in respective plates 36. In this way, the plates 36 can be adjustably clamped on the channels 37 by means of bolts 41, and place the rollers 31 in the desired spaced relation to the arms 18 with respect to the particular size of case being employed in the casing operation. From the roller conveyor 31 the case is transferred to a belt type discharge conveyor 46 of conventional construction.

From the above description it will be seen that the casing machine not only involves a split type support for the bottles at the casing station, but also provides a split type discharge support or conveyor, which extends inwardly into intersecting relation with the path of movement of the lift arms 18 in travelling after a case is discharged therefrom, the roller conveyors 31 being suitably spaced so as to permit the lift arms 18 to pass freely thereby. It will be noted also that the rollers 31a and 31b (Figure 1) are placed at different elevations so that the case at position 13a first engages the lower rollers 31a of the two roller conveyors, and then tilts over these rollers 31a to engage simultaneously the higher rollers 31b at position 13c. On further tilting movement as shown at the position of the case 13b in Figure 1 the case will be pivoting about the roller 31b and then engage the subsequent series of rollers 31 (see 13c) which are parallel therewith in a downwardly descending path so that a smooth discharge of the case is provided onto the discharge conveyor 46. This convex arrangement or configuration of the receiving end of the discharge roller type conveyors 31 provides a very smooth and easy discharge operation of the cases without undesirable jar accompanying the pivoting movement of the case. In effect a case is allowed to roll down to its position as shown in 13c in Figure 1 rather than to drop abruptly to this position. It will be further noted that the elevation of the roller conveyor 31 is such as to be engaged by the case 18 while it is still supported on the case support bars 21. The arrangement delivers a case to a slight higher discharge position than its lift position on the casing unit 12.

While I have shown and described a preferred em-

bodiment of the invention, it will be apparent that the invention is capable of modification and variation from the form shown so that the scope thereof should be limited only by the scope of the claims appended hereto.

I claim:

1. In a casing machine having means forming a plurality of parallel single file feed paths for containers, a casing station at a discharge end of said path having a corresponding plurality of split container supports open at one end, said supports being positioned to support an array of containers for insertion of a case thereover, a plurality of lift arms mounted for rotation about an axis transverse to said path and positioned to pass upwardly through said split supports to lift containers and the case therefrom, said lift arms having a home position in a plane inclined away from the vertical, and a plurality of rollers forming spaced apart discharge conveyor means disposed on the side opposite said lift arms from said container supports to receive a case from said arms, said conveyer means being spaced apart to provide for passage of said arms thereby, the forward ones of said rollers being positioned lower than the next adjacent ones of said rollers so that the case having containers therein is eased onto said discharge conveyer means from said lift arm without destructive impact.

2. In a casing machine having means forming a plurality of parallel single file feed paths for containers, a casing station at the discharge end of said paths comprising a corresponding plurality of split container supports open at one end, said supports being positioned to support an array of containers for insertion of a case thereover, a plurality of lift arms mounted for rotation about an axis transverse to said paths and positioned to pass upwardly through said split supports to lift containers therefrom, said lift arms having a home position in a plane inclined away from the vertical, and discharge conveyer means having its case receiving end spaced from the axis of rotation of said lift arms and having said case receiving end thereof disposed so that a case having containers therein is eased onto said conveyer means from said lift arms without destructive impact, said discharge conveyor means being split and spaced apart to provide for passage of said lift arms therethrough after discharge of a case therefrom, said split discharge means being positioned for engagement by the bottom of a case having its open end engaged with said lift arms, each said discharge conveyer means comprising a series of rollers with the endmost roller at its case receiving end positioned lower than the next adjacent roller.

3. In a casing machine having means forming a plurality of parallel single file feed paths for containers, a casing station at the discharge end of said paths having a corresponding plurality of spaced apart split container supports open at the end remote from said feed path forming means, said supports being positioned to sup-

port an array of containers for insertion of a case thereover, a plurality of parallel spaced lift arms mounted for rotation about an axis adjacent to the open ends of said container supports, and positioned to pass upwardly between and through said split supports to lift the containers and a case therefrom, said lift arms having a home position in a plane inclined away from the vertical, and a plurality of parallel spaced apart discharge conveyer means positioned on the opposite side of said axis from said container supports, the location and spacing of said discharge conveyer means providing for passage of said lift arms therewith in discharging a case of containers, said conveyer means having an upwardly facing convex configuration and the forward end of which is slightly above the horizontal plane of the axis of said container supports whereby to effect a rolling depositing action of a case on said conveyer means.

4. In a casing machine having means forming a plurality of parallel single file feed paths for containers, a casing station at the discharge end of said paths having a corresponding plurality of spaced apart container supports, said supports being positioned to support an array of containers for insertion of a case thereover, a plurality of parallel spaced lift arms mounted for rotation about an axis adjacent to one end of said container supports and having a home position inclined away from the vertical, said lift arms being positioned to pass upwardly between said supports to lift the containers and a case positioned over said containers, and a plurality of parallel spaced apart rollers comprising discharge conveyer means positioned on the opposite side of said axis from said container supports, said discharge conveyer means having spaces therebetween to provide for passage of said lift arms therethrough, the forward ones of said rollers being lower than the next succeeding ones of said rollers so that said conveyer means has an upwardly facing convex configuration to provide a hump in the intermediate part thereof so that a case being deposited thereon is given a rolling action without destructive impact.
